UNITED STATES PATENT OFFICE.

CLINTON B. ALEXANDER, OF WASHINGTON, DISTRICT OF COLUMBIA.

CASING AND METHOD OF MAKING THE SAME.

Application filed April 15, 1922. Serial No. 553,117.

This invention relates to casings, and more particularly to casings for use in a loose-leaf binder and adapted to have a cover hinged thereto.

5 It is one object of this invention to provide a tubular member or casing which will be of rugged structure and comprise but few parts, and an improved method of manufacture, whereby the making of the parts is 10 simplified and their assembly facilitated. It is also an object of the invention to provide a structure of this kind having parts so designed as to permit economical manufacture. It is a still further object of the invention to provide a simple and rugged metal hinge structure for a tubular member or casing of this type, and a simple and effective method of assembling the parts. Still further objects of the invention and the 15 features of novelty will be apparent from the following description when taken together with the accompanying drawing, in which:

Fig. 1 is a perspective fragmentary view 20 of a loose-leaf binder embodying one form of my invention;

Fig. 2 is a perspective view of certain of the parts, forming the casing shown in Fig. 1, before such parts are assembled;

30 Fig. 3 is a perspective view of the parts shown in Fig. 2, but in assembled relation;

Fig. 4 is a perspective view of a modified form of casing embodying my invention; and,

35 Figs. 5 and 6 are cross-sectional views of the channel members shown in Figs. 1 to 4, before assembly.

The binder shown in Fig. 1 comprises a top casing A and a base B, between which 40 loose leaves C are placed. Spaced posts, not shown, are rigidly mounted on the base B and project upwardly therefrom, suitable gripping mechanism being mounted in the casing A for releasably gripping the tops 45 of these posts which enter openings in the lower side of the casing. The leaves are placed in position on the posts, and the casing A is then placed in position to hold the leaves in place, it being understood that, 50 if desired, openings may be formed in the top of the casing A to permit the posts to extend therethrough. These details, as well

as the details of the releasable gripping mechanism, are not shown herein, since they constitute no part of the present invention. 55

A bottom cover D is hinged to the base B, the base comprising a flat metal strip E which is hinged to a similar flat metal strip F on the cover by forming offset hinge loops or lugs on the metal strips and passing a pin G 60 through the aligned openings in such lugs. It will be understood that, if desired, the bottom D may be made rigid with the base B, or may be connected thereto merely by the canvas, cloth, leather, paper, or other 65 flexible material with which the parts are commonly bound or covered.

As shown in Fig. 1, the casing A is provided with hinge loops or lugs H for co-operation with similar offset hinge loops or lugs I which are formed on a metal strip K rigidly secured, by rivets or in any other suitable manner, to a top cover L, a pin G' being passed through the aligned openings in the lugs H and I to hingedly connect the 75 cover L to the casing A.

The casing A comprises an inner channeled member M, a hinge member N and an outer channeled member O, these parts being formed as shown in detail in Fig. 2. The 80 member M has a substantially flat bottom portion from which side portions P extend in slightly diverging relation. The member O is formed with a bottom portion substantially flat, and with side portions Q 85 which extend in slightly converging relation from this bottom portion, the angle of convergence of these side portions Q being preferably somewhat less than the angle of divergence of the side portions P of the member M. One of the side portions Q of the member O is notched part way down, as shown at R, at the points at which hinge loops or lugs H, in any desirable number, are to be positioned, the notches having 90 slanting ends so as to form overhanging triangular projections S, for a purpose which will be later described. The hinge member N is a narrow flat strip of sheet metal having laterally extending portions, in any desirable number, bent at any appropriate and convenient angle thereto and curved to form the hinge lugs or loops H.

In assembling the parts of the casing A,

the triangular projections S, at the ends of notches R on the member O, are bent outwardly, as shown at the left in Fig. 2. The strip N is then placed in position in the member O, the lugs or loops H extending laterally from the notches R. With these two parts in position, the member M is assembled within the member O by pinching the side portions P, at one end of the member, toward each other and engaging such side portions P between the strip N and the side portion Q at the other side of the member O, and then telescopically moving the parts to the position shown in Fig. 3. The triangular projections S are now, in any suitable manner, bent back toward the inserted member M, in which position they bind the hinge lugs or loops H tightly in the notches R, so that the hinge loops H will be rigidly secured to the casing as a whole, and the parts will be firmly held in assembled relation. If the parts are properly proportioned, it is not always necessary to bend out all of the projections S, it being sometimes sufficient to bend out only the projection at the one end of each notch, the hinge lugs or loops H, when inserted, following the slope at the other end of the notch, as the parts are assembled.

Since the side portions Q converge slightly, and at an angle less than the angle of divergence of the side portions P, it is assured that, when members M and O are telescopically assembled, the lower edges of the side portions P will slide on the bottom portion of the member O, and the hinge strip N will be held securely by reason of the fact that it is clamped between the side portions P and Q. If desired, the casing may be made more rigid by tapping the upper edges of the side portions Q with a hammer, after the parts are assembled, to compress them against the top of the inner casing member M.

If, instead of the metal hinge, it is desired to utilize as a hinge the canvas, cloth, leather or other flexible material commonly used as a binding or covering for the casing A and the cover L, the casing is preferably made as shown in Fig. 4. In this modification, the hinge strip is omitted, the casing being formed of an inner casing member T, identical with the member M, shown in Figs. 1 to 3, and an outer casing member U, similar to member O, shown in Figs. 1 to 3, but having no notches cut therein. It will be appreciated that, if desired, the member U may be made of slightly less width than the member O, but it is preferable that the parts be so proportioned as to have a snug fit, whether the thickness of the hinge strip is interposed or not, so that either modification may be made from strip material of the same width, without change except as to the formation of notches R. It will also be understood that

when desired, either of the casings shown may be covered with a wrapping of glued paper, cloth, or other suitable paper to prevent rust, such covering still further enhancing the rigidity of the casing, and that there will be no rough surfaces tending to cut such covering or mar the appearance thereof.

It will be apparent that the structures herein shown and described may be cheaply manufactured, the channeled members being formed from strip material, and the assembly requiring the simple step of telescoping the parts together. It will also be apparent that an additional step such as riveting over interlocking projections is avoided, and that the parts will form a rigid casing capable of withstanding the strains incident to use.

Having thus described my invention, it will be understood that changes may be made in the details of structure and assembly without departing from the spirit of the invention which is defined in the following claims.

What I claim is:

1. In a loose leaf binder construction, a casing comprising two metal channeled members of uniform cross section from end to end having flat base portions and flat side walls extending in opposite directions from their base portions, the side walls of one of said members being in diverging relation and resiliently received between and substantially parallel with the side walls of the other of said members.

2. In a loose leaf binder construction, a casing comprising an inner channeled member and an outer channeled member each having flat side walls and of uniform cross section from end to end, one of said members being inverted with respect to the other, the side walls of the inner channeled member being resiliently held between the side walls of the outer channeled member and the edges of the side walls of the inner channeled member engaging the bottom of the outer channeled member.

3. The combination of an inner channeled member and an outer channeled member, one of said members being inverted with respect to the other, and a member having hinge loops and having a portion resiliently held between a side wall of said inner channeled member and the corresponding side wall of said outer channeled member.

4. The combination of an inner channeled member and an outer channeled member, said outer channeled member being inverted with respect to the inner channeled member and having a notch formed in one of its side walls, and a hinge member having a portion between said wall of the outer channeled member and the adjacent wall of the inner channeled member and having a hinge portion extending through said notch.

5. The combination of an inner channeled

member and an outer channeled member, said outer channeled member being inverted with respect to the inner channeled member and having a notch formed in one of its side walls, and a hinge member having a portion between said wall of the outer channeled member and the adjacent wall of the inner channeled member and having a hinge portion extending through said notch, the wall of said outer channeled member having projections overhanging the notch therein.

6. The combination of an inner channeled member and an outer channeled member, said outer channeled member being inverted with respect to the inner channeled member and having a notch formed in one of its side walls, and a hinge member having a portion between said wall of the outer channeled member and the adjacent wall of the inner channeled member and having a hinge portion extending through said notch, the wall of said outer channeled member having a portion resiliently held between said side wall and the adjacent side wall of said outer channeled member, said outer member having means integral therewith for retaining said hinge portion seated in the notch.

7. In a loose leaf binder, a casing comprising adjacent inner and outer walls, said outer wall being formed with an opening, and a hinge member having a portion between said walls and a hinge portion extending through said opening.

8. In a loose leaf binder, a casing comprising adjacent inner and outer walls, said outer wall being formed with an opening, and a hinge member having a portion between said walls and a hinge portion extending through said opening, said outer wall having means integral therewith for retaining said hinge portion seated in the opening therein.

9. In a loose leaf binder, a casing comprising adjacent inner and outer walls, said outer wall being formed with an opening, and a hinge member having a portion clamped between said walls and a hinge portion extending through said opening.

10. In a loose leaf binder, a casing comprising adjacent inner and outer walls, said outer wall being formed with an opening, and a hinge member having a portion resiliently held between said walls and a hinge portion extending through said opening, said outer wall having means integral therewith for retaining said hinge portion seated in the opening therein.

11. In a binder, the combination of an inner channeled member and an outer channeled member, one of said members being inverted with respect to the other, said inner member having its side walls in diverging relation, and said outer member having its side walls in converging relation, one side wall of said outer member having an opening formed therein, and a hinge member having a portion extending through said opening and a portion resiliently held between

said side wall and the adjacent side wall of said inner channeled member.

12. In a binder, the combination of an inner channeled member and an outer channeled member, one of said members being inverted with respect to the other, said inner member having its side walls in diverging relation, and said outer member having its side walls in converging relation, one side wall of said outer member having an opening formed therein, and a hinge member having a portion extending through said opening and a portion resiliently held between said side wall and the adjacent side wall of said inner channeled member, said outer member having means integral therewith for retaining said hinge portion seated in the opening.

13. The process of forming a binder casing comprising forming a channeled member with flat side walls in converging relation and a second channeled member with flat side walls in diverging relation, each of said channeled members being of uniform cross section from end to end, compressing together the end portions of the walls of said second channeled member and inserting them within an end of said first channeled member with said channeled members in inverted relation, and sliding said channeled members together longitudinally.

14. The process of forming a binder casing comprising, forming a pair of channeled members, forming a strip with hinge lugs, inserting said strip in one of said channeled members in engagement with one side wall thereof, and telescopically engaging the other of said channeled members within said first mentioned channeled member and in inverted relation thereto.

15. The process of forming a binder casing comprising, forming a channeled member with diverging side walls, forming a second channeled member with converging side walls and with a notch in one of said side walls, forming a hinge member with a flat portion and a hinge lug, engaging the flat portion of said hinge member with said notched wall with the lug thereon extending through said notch, and telescopically engaging said first channeled member within the second channeled member, while inverted relative thereto, with its side walls between the flat portion of said hinge member and the opposite side wall of said second channeled member.

16. The process of securing a hinge member to a casing which comprises forming one wall of the casing with a notch having an overhanging projection, bending said projection outwardly, engaging the hinge member with the inner surface of said wall with its hinge lug extending through said notch, and bending said projection back to overhang said hinge lug.

17. The process of forming a hinged casting which comprises forming a channeled member with a notch in one side wall and a projection overhanging said notch, forming a member with a hinge lug, forming a second channeled member, bending said projection outwardly, inserting said hinge member within said first channeled member with its

hinge lug extending through said notch, engaging said second channeled member within said first channeled member and in inverted relationship thereto, and bending back said projection to overhang said lug. 10

In testimony whereof I have affixed my signature.

CLINTON B. ALEXANDER.
